TUBING STOP

Charles F. Moseley, Bartlesville, Okla.

Application June 26, 1936, Serial No. 87,579

14 Claims. (Cl. 103—219)

The present invention relates to apparatus for use in oil or water wells and relates particularly to improved tubing catchers or tubing stops.

It is an object of this invention to provide an improved form of tubing stop which will permit tubing to be anchored in a well casing at any desired point and which will permit ready disengagement of the device from the sides of the well casing whenever it is desired to remove or reset the tubing.

In most, if not all, of the tubing catchers or stops now in use, a solid cone or mandrel mounted on the tubing is used to spread collapsible slips so that they may engage the walls of the well casing at the desired point, the weight of the tubing then acting on the cone to retain the slips in their spread position. The use of such devices is subject to at least one major difficulty which it is the purpose of my invention to overcome. When the tubing has been set and the cone pressed against the slips causing teeth on the slips to engage the casing walls, such cones, because of the relatively large surface area thereof which is in contact with the back of the slips and after remaining in the well for a long period of time subject to the corrosive and rusting action of well fluid, are wont to "freeze" to the slips and oppose effort to withdraw same from engagement with the slips so that the slips may be collapsed to permit the entire structure to be removed from the well or to be reset at another point in the well casing.

It is a principal object of my invention to provide a form of collapsible cone formed in segments on which the slips are slideable and which are in turn acted upon by a spreader plate or mandrel to force the teeth on the slips into engagement with the well casing. Said spreader plate or mandrel is in the form of a relatively flat frustum of a cone, the outside of which may be smooth or formed in a series of steps or shoulders, or otherwise, so that the total amount of the surface of the mandrel contacting the corresponding surfaces of the collapsible cone segments is relatively much less than in the case of the solid cones hitherto in use, and the danger of "freezing" to the slips will thereby be greatly minimized.

Another object of my invention is to provide a tubing stop constructed generally as above described which when used in inverted position will function as a highly efficient fishing tool for withdrawal of casing or tubing from a well and one which may be readily disengaged from the

casing or tubing when down below the surface of the ground.

Other objects and advantages of my new invention will be readily apparent from the following detailed description when read in conjunction with the attached drawings, in which:

Fig. 1 is an elevation, partially sectional, of a form of my invention showing slips in the collapsed position for free movement within the well casing;

Fig. 2 is a similar view of the device in operative position anchored within the well casing;

Fig. 3 is a detail of the latching slot for holding the slips in the collapsed or engaging position;

Fig. 4 is a detail of one of the segments of the collapsible cone;

Figs. 5, 6 and 7 are sections taken along lines 5—5, 6—6 and 7—7, respectively, of Fig. 1;

Fig. 8 is a vertical sectional elevation showing, in collapsed position, a modified form of my device when used as a fishing tool; and

Fig. 9 is a view similar to that shown in Fig. 8 but showing the slips and cone in operative or engaging relationship with well casing.

Like numbers indicate like parts in the several drawings.

Referring to Fig. 1, there is shown a section of well bore or casing 10 in which is inserted a section of well string or tubing 11 adapted to be set or anchored in casing 10 on which is mounted the device of my invention, which consists of an elongated sleeve member 12 surrounding tubing 11 and spaced therefrom a suitable distance so as to form a generally annular chamber between 30 tubing 11 and sleeve 12. Extending from the inner wall of sleeve 12 toward tubing 11 is a ring 13 encompassing tubing 11 but not in contact therewith. Ring 13 divides the annular space between tubing 11 and sleeve 12 into a 35 lower chamber 14 and an upper chamber 15. In the lower chamber 14 is a coil spring 16 surrounding tubing 11 and held in place against ring 13 by a follower 17 which is fixedly mounted on tubing 11 and extends into the lower end of 40 chamber 14. The outer surface of chamber 14 is of angular contour, as in the form of a square, and the outer surface of follower 17 is complementary in shape (see Fig. 7) to permit telescoping of follower 17 into chamber 14 while preventing turning of sleeve 12 relative to follower 17 and to thereby cause sleeve 12 to turn with tubing 11 since follower 17 is fixedly attached to tubing 11. A cage 18 on which are mounted bow 45 springs 19 surrounds the lower portion of sleeve 12.

Another object of my invention is to provide a tubing stop constructed generally as above described which when used in inverted position will function as a highly efficient fishing tool for withdrawal of casing or tubing from a well and one which may be readily disengaged from the

12 and lugs 20 extend inwardly from the upper edge of cage 18 and engage L shaped slots 21 (Fig 3) located in about the center of sleeve 12 and serve to hold cage 18 in engagement with 5 sleeve 12, and slots 21 cooperate with lugs 20 to limit the vertical and lateral movement of cage 18 with relation to sleeve 12. Bow springs 19 are adapted to frictionally engage the inner walls of casing 10, the tension of bow springs 19 being 10 sufficient to support the weight of cage 18 by frictional pressure exerted by springs 19 against the walls of casing 10.

The upper end of sleeve 12 terminates in a U shaped member 22, the opening of the U pointing upward. The outer prong of the U turns inwardly toward tubing 11 forming an annular lip 23 tending to partially close the opening of the U thus forming an annular slot 24 in the upper end of sleeve 12, said slot 24 opening upwardly. 15 A series of arc shaped plates 25 forming a collapsible cone are mounted in slots 24 by means of tongues 26 having outwardly turned lips 27 which engage the inwardly extending lips 23 forming hinge type joints which permit plates 25 to swing 20 toward or away from casing 10. Plates 25 are spaced apart from each other a sufficient distance to permit of movement of plates 25 towards each other when they move in a direction 25 away from the walls of casing 10 in assuming the 30 collapsed position of Fig. 1. All of the plates 25 together form the collapsible cone which is one of the principal features of my invention. The maximum spread of plates 25 is regulated by means of straps 28, each of which has one end 35 fixedly attached to one of plates 25 by means of a bolt 29 and the other end attached to an adjacent plate 25 by means of another bolt 30 which is slidably engaged in a slot 31 in strap 28. (Fig. 4.) By this means plates 25 may swing 40 inwardly toward tubing 11 to the extent permitted by slots 31 in straps 28 and outwardly toward casing 10 to the same extent. The maximum outward movement of plates 25 is such that the maximum outside diameter of the cone formed by plates 25 in their most extended position will be less than the inside diameter of casing 10.

The upper edges of plates 25 are tapered upwardly and outwardly in a series of circular steps 50 or seats 32. A mandrel 33 fixedly attached to tubing 11 above the plates 25, is formed in the shape of a frustum of a cone, the outer surface of which is tapered inwardly and downwardly in a series of circular steps or shoulders 34 adapted 55 to be seated in seats 32 when mandrel 33 is brought into contact with plates 25. As noted above, the upper edges of plates 25 may form a smooth conical seat and the outer surface of mandrel 33 may have a corresponding shape. 60 The taper of the upper edges of plates 25 may be greater than that of mandrel 33 so that the points of contact of plates 25 with mandrel 33 will form a narrow ring, or in the case of the step-wise taper illustrated, will form a series of 65 concentric contact rings. The chief point to be noted is that the total surface thus in contact between plates 25 and mandrel 33 is kept very small for reasons to be more fully explained hereinafter.

70 A metal ring 35 encompasses sleeve 12 between cage 18 and the U shaped end 22 of sleeve 12 and is slideable on sleeve 12 between these points. Attached to ring 35 by resilient arms 36 and extending thereabove are arc-shaped slips 37 on 75 the outer faces of which are teeth 38. The inner

faces of slips 37 form surfaces tapering upwardly and complementary in shape to the outer faces of plates 25, with which they are in slideable engagement. Lugs 39 extend from the inner faces of slips 37 through elongated slots 40 5 formed in plates 25 which limit the movement of slips 37 over plates 25 to a vertical direction. Slots 40 are of sufficient length to permit the maximum required amount of such movement. Heads 41 on lugs 39 prevent disengagement of 10 slips 37 from plates 25.

The manner in which the above described device functions is as follows:

The device, in the collapsed position illustrated in Fig. 1, is inserted in casing 10. In this position 15 lugs 20 are engaged in the lateral arms of L shaped slots 21 and in this position slips 37 will be located toward the lower ends of plates 25 which are seated against mandrel 33 by the tension of spring 16 which is designed to hold plates 20 25 in this seated engagement. When the device has reached the desired point in casing 10, tubing 11 is turned so as to disengage lugs 20 from the lateral arms of slots 21. The frictional engagement of bow springs 19 will hold cage 18 and 25 lugs 20 in position so this turning movement may be effected. When the turning movement has reached the point where lugs 20 will enter the vertical arms of slots 21, cage 18 will remain stationary and tubing 11 with sleeve 12 and its 30 attached elements will be permitted to continue downward whereupon ring 35 will come in contact with the upper end of cage 18 and acting through arms 36 will force slips 37 to move upwardly and outwardly over the outward faces 35 of plates 25 until teeth 38 engage and bite into the walls of casing 10 as shown in Fig. 2. The continued downward movement of tubing 11 will continue to apply increasing pressure as more of the weight of tubing 11 on mandrel 33 is applied 40 through plates 25 to slips 37 until teeth 38 are firmly imbedded in casing 10 and tubing 11 will then be firmly anchored, as long as the weight of the tubing rests on plates 25 in the manner described.

When it becomes necessary to remove the tubing from the well or to change its position within the casing, an upward pull is applied to the tubing 11 at the mouth of the well, in the usual manner, whereupon follower 17 will act to compress spring 16 sufficiently to permit mandrel 33 50 to be lifted out of engagement with seats 32 on plates 25, thereupon permitting plates 25 to collapse inwardly toward tubing 11 sufficiently to permit teeth 38 on slips 37 to spring out of engagement with casing 10 whereupon spring 16 55 will expand forcing plates 25 upwardly into proper seating engagement with mandrel 33 and as a result of this movement slips 37 will move downwardly over plates 25 and will again reach 60 the position shown in Fig. 1, whereupon lugs 20 will again be in register with the lateral arms of slots 21 and a turn of tubing 11 will bring lugs 20 into the lateral arms of slots 21 thus locking slips 37 in their collapsed position and permitting 65 the device together with the tubing 11 to be withdrawn from the casing 10 or to be moved to another position therein.

It will be evident that by means of my device I utilize a principle of applying the weight of tubing 11 to a relatively small area such as the small circular contact areas between seats 32 and shoulders 34, and in this way, there can be no large cone surfaces to "freeze" to the slips. Even if we assume that slips 37 "freeze" to plates 25, 70 75

when the weight of tubing 11 is lifted from seats 32 of plates 25, the tension in the walls of casing 10 which naturally resists the outward pressure of slips 37 when pressure due to the weight of tubing 11 is applied thereto, will cause slips 37 and plates 25 to spring inwardly and bring teeth 38 out of engagement with casing 10. The great advantage of my form of tubing anchor or stop over present forms will be clearly evident when it is noted that the present forms of tubing anchors employ solid cones fixedly attached to the tubing or other support means, and that said cones bear directly against the slips. In such devices the only way to lift the weight of the tubing from the slips is to pull the cones out of engagement with the slips and, as pointed out above, when "freezing" has set in over the relatively large contact surfaces between such cones and slips, it becomes, in many cases, impossible to accomplish this separation with the result that the tubing is frequently pulled in two in the effort to release the tubing stop.

In Figs. 8 and 9 I have illustrated a slightly modified form of my invention whereby the device may be utilized as a fishing tool or casing spear. This is accomplished by inverting the device and making one simple mechanical change in the structure above described.

The numbers on Figs. 8 and 9 denote the same elements in their same relative relationship as designated by these same numbers in the preceding figures with the following slight modifications:

In the device illustrated in Figs. 8 and 9, ring 35 to which is attached arms 36 carrying slips 37 and the end of cage 18 from which lugs 20 extend into slots 21 in sleeve 12 are modified in form, over that shown in the above described device, so as to be joined together to form a swivel joint 42, and on mandrel 33 is mounted a spear point 43 to aid in guiding the device into casing 10. When the device of my invention is to be used as a fishing tool it is inserted into the casing or tubing to be pulled in the inverted position shown in Figs. 8 and 9.

When used as a fishing tool the device functions in the following manner:

When the device is in the collapsed position of Fig. 8, lugs 20 are engaged in the lateral arms of slots 21 in which position the slips 37 are positioned on plates 25 at a point closest to the end member 22 of sleeve 12. When the device has been inserted in casing 10 to the desired position therein, tubing 11 is turned to disengage lugs 20 from the lateral arms of slots 21 and lugs 20 are thereby moved into the vertical arms of slots 21, whereupon a lift or pull is taken on tubing 11. The upward movement of tubing 11 will cause plates 25 to move up over slips 37 and the outward taper of plates 25 will force slips 37 toward the walls of casing 10 until teeth 38 bite into the walls of casing 10. The continued upward movement of tubing 11 will bring pressure to bear through mandrel 33 on the contact surfaces of plates 25 and will thus act to firmly press teeth 38 on slips 37 into the walls of casing 10 and will hold the slips in firm engagement with casing 10 as long as the pull is exerted on tubing 11. When it is desired to release the hold of the device on casing 10, the pull on tubing 11 is slackened and tubing 11 is permitted to start downward into casing 10, whereupon follower 17 will act upon spring 16 compressing it sufficiently to permit mandrel 33 to move downward out of engagement with seats 32 on plates 25. Thereupon plates 25

will collapse permitting slips 37 to spring inwardly pulling teeth 38 out of engagement with casing 10. Spring 16 will then expand forcing plates 25 down over slips 37 and bring seats 32 again into contact with shoulders 34 on mandrel 33 and will at the same time bring lugs 20 upward in slots 21 until lugs 20 register with the lateral arms of slots 21 whereupon tubing 11 is turned sufficiently to engage lugs 20 in the lateral arms of slots 21 locking slips 37 in the collapsed or inoperative position in exactly the same manner as described above. The entire device may then be withdrawn from casing 10.

Here again it will be evident that even though plates 25 may tend to "freeze" to slips 37, compression of spring 16 will permit mandrel 33 to move out of contact with seats 32 a distance sufficiently great to permit slips 37 and plates 25 to collapse inwardly toward tubing 11 as a result of the tension in the walls of casing 10 and thus free slips 37 from the walls of casing 10.

It will be evident that numerous modifications may be made in the elements of my device. For example, mandrel 33, instead of being solid as shown, may be in the form of a spider with spaces 25 between the arms thereof to permit ready passage of well fluids therethrough. In this form there may be one or more arms of the spider in contact with each of the plates 25 in which case the area of contact between the spider arms and plates 25 will consist of a series of arcs. From a practical standpoint it is only necessary that the arms of the spider shaped mandrel be sufficiently strong to support the weight of the tubing and sufficiently stiff to prevent the tension in the walls of casing 10 from forcing plates 25 inwardly by overcoming the resistance of the spider arms to such movement.

The number of slips 37 and cone segments or plates 25 may be varied as desired depending upon the size of the casing in which the tubing is to be anchored.

When the device is used as a fishing tool, tubing 11 may be replaced by a solid metal member to obtain greater strength.

In the forms of my new device illustrated herein, arms 36 attached to rings 35 and supporting slips 37 are shown as flat bars. These may be spring steel to allow sufficient outward spring of slips 37 in order that slips 37 may engage casing 10 and also to assist in causing slips 37 to pull out of engagement with casing 10 when the pressure of the tubing is removed. Also arms 36, instead of being solidly attached to ring 35 as shown, may be attached thereto by a hinge device.

Various other modifications in shape, size and form of the elements of the device will no doubt be apparent to those skilled in the art without occasioning a departure from the scope of my invention as set forth in the appended claims.

It will also be apparent to those skilled in the art that my new device may be combined with packers in the manner well understood in this particular art. By providing automatic means for unlatching the slips my device may be readily converted into a true tubing catcher rather than the tubing stop herein described in detail.

The fishing tool shown in Figs. 8 and 9 is claimed specifically in my divisional application Serial No. 160,923, filed August 25, 1937.

What I claim and desire to secure by Letters Patent is:

1. In a device of the character described, a well string, a collapsible cone comprising segmental members supported by said string, slips

slidably engaging said cone, and means on the well string for holding said cone in expanded condition, said means being movable axially of the well string away from the cone to allow the latter to collapse toward the well string.

2. In a device of the character described, a well string, a collapsible cone comprising segmental members supported by said string, slips slidably engaging said cone, and means on the well string for holding said cone in expanded condition, said means being movable away from the cone to allow the latter to collapse toward the well string, the last mentioned means including a substantially disk-shaped mandrel engageable with one end portion of each of the segmental members.

3. In a device of the character described, a well string, a collapsible cone comprising segmental members supported by said string, slips slidably engaging said members and adapted to interlock with the bore of a well, and means movable axially of the well string into and out of engagement with one end portion of each of said segmental members for holding the cone in expanded condition.

4. In a device of the character described, a well string, a collapsible cone comprising segmental members supported by said string, slips slidably engaging said members and adapted to interlock with the bore of a well, means movable axially of the well string into and out of engagement with one end portion of each of said segmental members for holding the cone in expanded condition, and means actuated by movement of the string relatively to said members for setting and releasing said slips.

5. A tubing stop including a tubing, a collapsible cone comprising segmental members supported by said tubing, slips slidably engaged on said members, and weight carrying means attached to said tubing and contacting said members whereby pressure is applied to said members to force said slips into anchoring engagement with a casing.

6. A tubing stop as claimed in claim 5, wherein the contacting surfaces between said weight carrying means and said members are line contacts.

7. In a device of the character described, a well string, a follower supported thereby, a sleeve slidably mounted on the string, a spring coacting with the sleeve and follower for normally urging the sleeve in a direction away from the follower, a cage mounted on the sleeve and provided with friction means engageable with the bore of a well for holding the cage in a fixed position while the sleeve is moved relatively thereto, a slip assembly cooperating with the cage, a collapsible cone supported by the sleeve and including segmental members slidably engaging the slips, and means supported by the well string for holding the cone in expanded condition, the last mentioned means being movable axially of the well string away from the cone to allow the latter to collapse.

8. In a structure of the character described, a well string, a member supported by the well string, a collapsible cone including segmental members hingedly connected at one end to the first mentioned member, a slip assembly having slips slidably engaging the segmental members and adapted to interlock with well casing, and a substantially disk-shaped mandrel engageable with the other ends of the segmental members for normally holding the cone in expanded condition,

said mandrel being movable away from the cone to allow the latter to collapse.

9. In a structure of the character described, a well string, a member supported by the string, a collapsible cone including segmental members, each having one of its ends hingedly connected to the first mentioned member, toothed slips slidably engaging the cone and adapted to grip the bore of well casing, and a substantially disk-shaped mandrel having a relatively short annular surface engageable with the opposite end portions of the segmental members for normally holding the cone in expanded condition, said mandrel being movable away from the segmental members to allow the cone to collapse.

10. In a structure of the character described, a well string, a sleeve supported by the string, a collapsible cone including segmental members, each having one of its ends hinged to the sleeve, toothed slips slidably engaging the segmental members, slot and pin connections joining the slips to said members, means mounted on the sleeve and adapted to frictionally engage the bore of a well for setting and releasing said slips, a substantially disk-shaped mandrel engaging the opposite ends of the segmental members for normally holding the cone in expanded condition, said mandrel being movable with the well string relatively to the cone for releasing the mandrel from the cone to permit collapsing of the latter.

11. In a structure of the character described, a well string, a sleeve supported thereby and movably arranged relatively to the well string, a cage, a slot and pin connection joining the cage to the sleeve, friction means carried by the cage and engageable with the bore of a well for holding the cage in a fixed position while the sleeve moves relatively thereto, a slip assembly engageable with the cage, toothed slips forming part of said assembly and adapted to be set by movement of the sleeve relatively to the cage and slip assembly, a collapsible cone including segmental members, each having one of its ends hingedly connected to the sleeve, said slips slidably engaging said segmental members, and a substantially disk-shaped mandrel supported by the well string and engageable with the opposite end portions of the segmental members for normally holding the cone in expanded condition.

12. In a structure of the character described, a well string, a sleeve supported by and movably arranged relatively to the well string, a cage, a slot and pin connection joining the cage to the sleeve, friction means carried by the cage and engageable with the bore of a well for holding the cage in a fixed position while the sleeve moves relatively thereto, a slip assembly engageable with the cage, toothed slips forming part of said assembly and adapted to be set by movement of the sleeve relatively to the cage and slip assembly, a collapsible cone including segmental members, each having one of its ends hingedly connected to the sleeve, said slips slidably engaging said segmental members, and a substantially disk shaped mandrel supported by the well string and engageable with the opposite end portions of the segmental members for normally holding the cone in expanded condition.

13. In a structure of the character described, a well string, a sleeve supported by and movably arranged relatively to the well string, a cage, a slot and pin connection joining the cage to the sleeve, friction means carried by the cage and engageable with the bore of a well for holding

the cage in a fixed position while the sleeve moves relatively thereto, a slip assembly engageable with the cage, toothed slips forming part of said assembly and adapted to be set by movement of the sleeve relatively to the cage and slip assembly, a collapsible cone including segmental members, each having one of its ends hingedly connected to the sleeve, said slips slidably engaging said segmental members, a substantially disk-shaped mandrel supported by the well string and engageable with the opposite end portions of the segmental members for normally holding the cone in expanded condition, and means for limit-

ing the expanding movement of the segmental members.

14. A device of the character described, comprising a well string, a collapsible cone supported by the string and comprising segmental members, means hingedly supporting said members from the lower ends thereof, toothed slips slidably engaging said members, means arranged below the members for setting said slips, and a relatively short mandrel engageable with the upper end portions of said members for normally holding the cone in expanded condition. 5

CHARLES F. MOSELEY.
